ROBERT T. McCONLOGUE, OF FREEPORT, NEW YORK, ASSIGNOR OF ONE-HALF TO
ROBERT A. PATRICK, OF FREEPORT, NEW YORK.

THERMOSTATIC VALVE.

1,161,060.

Specification of Letters Patent. Patented Nov. 23, 1915.

Application filed March 11, 1915. Serial No. 13,740.

To all whom it may concern:

Be it known that I, ROBERT T. McCONLOGUE, a citizen of the United States, and resident of Freeport, county of Nassau, and 5 State of New York, have invented certain new and useful Improvements in Thermostatic Valves, of which the following is a specification.

In line casting machines there are usually 10 two gas burners, one for the melting pot and the other for the lip of the discharging spout through which the metal is passed to the mold. These burners maintain different temperatures. The melting pot temperature is considerably lower than the temperature of the lip through which the metal is discharged into the mold. The burner under the pot is considerably larger than the lip burner and, of course, requires a 15 larger supply of gas. Heretofore it has been extremely difficult to maintain the two burners properly supplied with gas so that the temperature of the lip would at all times be higher than the temperature of the pot. 20 The supply of gas to each burner has heretofore been controlled by a separate valve. There has been no means by which the temperature of the lip could be controlled from the melting pot. In view of the fact that 25 the temperature of the lip must be higher than the temperature of the molten metal in order that the metal will properly discharge through the lip, it is very desirable that the supply of gas to the lip burner 30 should be controlled by the temperature of the molten metal in the melting pot.

One of the main objects of this invention is to provide a thermostatic valve adapted to control the supply of gas to two or 40 more burners, said burners being adapted to produce different temperatures.

Another object of the invention is to provide a valve adapted to control the supply of gas to two or more burners, said burners 45 receiving different quantities of gas and each burner having a pilot flame.

Another object of the invention is to provide a valve adapted to control the supply of gas to two or more burners, said valve 50 being adapted to cut off both burners from the gas supply, except that a small quantity of gas will be fed to a pilot flame at each burner at all times, whether the valve be opened or closed.

55 There are many other objects and advan-

tages of the invention, which will be more fully hereinafter set forth and relating to the thermostatic element and the parts immediately adjacent thereto and operated thereby.

In the drawings, Figure 1 is a vertical sectional view of the thermostatic element and the controlling valve connected therewith, taken on the line I—I of Fig. 2; Fig. 2 a transverse sectional view of the valve 60 taken on the line II—II of Fig. 1; and Fig. 3 a plan view of the under side of the valve seat.

Referring to the various parts by numerals, 1 is the gas supply pipe which may be 70 of any suitable form and may be provided with suitable swivel joints 2 to enable the valve and its connected parts to be properly arranged in any machine to which it is to be attached. The valve casing 3 is provided with a lower gas chamber 4 to which the gas supply pipe 1 is connected. Fitted in the valve casing and serving as a closure for the gas chamber 4 is a downwardly tapered plug 6. In the lower face of this 75 plug is formed two annular channels 7 and 8. The walls of these channels are tapered to their lower ends to form annular knife-edge valve seats 9 and 10, the seat 10 being the separating wall between channel 7 and 80 channel 8.

The valve casing 3, on opposite sides of the chamber 4, is provided with two inlet 85 passages 11 and 12, said passages extending upwardly from the bottom of the casing. The upper end of passage 11 is in communication with channel 7 through the port 13; and the channel 7 is in communication with passage 12 through a port 14. Port 13 is larger in diameter than port 14, and, 90 therefore, has a larger capacity. Ports 15 and 16 connect passages 11 and 12, respectively, to the lower gas chamber 4. Gas supply pipes 17 and 18 lead from the lower 95 ends of the passages 11 and 12, respectively, to the burners. Gas constantly passes through ports 15 and 16 to supply the pilot lights at the burners, and these ports are regulated by needle valves 19 of any suitable construction. Supply pipe 18 is connected to the lip burner and the quantity of 100 gas supplied to said burner when the valve is open is regulated by means of a needle valve 20 which is adapted to control the outlet from port 14.

To close the channels 7 and 8 simultaneously and thereby shut off the main supply of gas to the burners I provide a metal disk valve 21 carried by a stem 22 which extends upwardly through the plug 6. This valve is maintained seated by means of a spring 23 located in the main gas chamber 4. It will be readily understood that when this valve is seated the channels 7 and 8 are cut off from communication with the chamber 4, and also passage 11 is sealed from passage 12 except for the small amount of gas passing from the main gas chamber through the pilot valve ports 15 and 16. The valve stem 22 is packed gas-tight by means of a series of annular grooves 22^a formed in the bearing 22^b of said stem. These grooves are filled with oil or other similar material and prevent the escape of gas along the stem from chamber 8.

The thermostatic element consists of an iron container 24 which is threaded at its upper end into a lateral extension 25 of the plug 6 and held adjustably therein by means of a lock nut 26. In this container is arranged a long carbon rod 27 on the upper end of which rests a metal block 28, the upper end of which is adapted to constantly bear on the short arm 29 of a lever 30, the said block engaging a semi-spherical projection 31 on the under side of said lever. A rod of any other material having a low coefficient of expansion, such as lava, may be substituted for the carbon rod, and it is, of course, to be understood that I am not to be limited to the use of any particular material for this element of the thermostat. The forward end of valve operating arm 30 carries a screw 32 the lower end of which is adapted to bear against the upper end of the valve rod 22, said lower end being made semi-spherical as shown. To adjust the screw in the end of the said arm I provide an adjusting device 33 carried by the screw and adapted to be swung from side to side to increase or decrease the projection of the screw below the lever 30. This regulates the extent of opening of the valve 21. The adjusting device 33 may be arranged to be moved over a scale arranged on the side of the casing near the upper end thereof, said scale indicating the degree of opening of the valve and the resulting temperatures in the melting pot and at the discharge lip.

In order to protect the parts of the apparatus I provide an inclosing casing 34 for the lever 30 and the upper end of the thermostatic elements; and also a pivoted cap 35 which incloses the upper end of the valve stem, the regulating screw and the screw adjusting device.

The plug 6 is held in place by means of bolts and nuts 36.

The operation of the device may be briefly described as follows: The thermostatic con-

tainer element is placed in the melting pot of a line or other casting machine and the pipes 17 and 18 properly connected to the respective burners. When the temperature in the melting pot has reached the desired point the iron container 24 has expanded sufficiently to permit the carbon rod and the operating block to drop away from the short arm of the lever. This permits the spring 23 to seat the valve disk on the knife-edge 75 seats 9 and 10, thereby shutting off gas from the ports 13 and 14. Gas will continue to flow through the pilot light ports 15 and 16 in the desired quantity. When the temperature of the molten metal in the melting pot is reduced by the addition of metal the container 24 will contract and thereby force upwardly the carbon rod and the operating block, and as the block bears constantly on the short arm of the lever 30 said lever will be swung on its pivot and the valve 21 depressed against the action of the spring 23. Gas will again flow through the channels 7 and 8 and ports 13 and 14 to the burners in the desired regulated quantities. By moving the adjusting device 33, the extent of movement of the valve 21 may be varied to thereby vary the quantity of gas supplied to the burners. By reason of the restricted port 14 and the needle valve 20 the quantity of gas supplied to the lip burner will be smaller than that supplied to the melting pot burner, the said quantities being maintained in a certain proportion to each other throughout all the variations in the valve 100 opening. It will, of course, be understood that the carbon rod expands much less than the iron container under the same degree of heat and that consequently the carbon rod will be given a vertical movement by reason 105 of the expansion and contraction of the iron container 24.

It will, of course, be understood that this thermostatic valve may be used to control the supply of gas to any number of burners independently and I do not wish to be limited to the application of it for the control of the two burners.

What I claim is:

1. A thermostatic valve comprising thermostatic elements, a valve casing formed with a gas supply chamber, a plurality of independent outlet ports from said chamber, a single valve adapted to close all of said outlet ports simultaneously, means operatively connecting said valve to the thermostatic elements whereby said valve will be opened upon a decrease of temperature in the thermostatic elements and will be closed upon an increase of temperature in 125 said elements.

2. A thermostatic valve comprising a valve casing formed with a gas chamber, a plurality of independent ports leading from said chamber, a gas supply leading to 130

5 said chamber, a single valve to close communication between said chamber and all of the said ports simultaneously and also at the same time to close communication between the ports, thermostatic elements, and means connecting said elements to said valve whereby an increase of temperature in the elements will close the valve and a reduction in the temperature of the elements will 10 open said valve.

6 3. A thermostatic valve comprising a valve casing formed with a gas chamber and a plurality of independent gas passages adapted to be connected to independent 15 burners, an independent port leading from the gas chamber to each of said passages, a single valve adapted to close communication between the gas chamber and all of the said ports simultaneously, pilot light ports 20 between the gas chamber and said passages, said pilot light ports being uncontrolled by the said valve, thermostatic elements, and means operatively connecting said elements to said valve whereby an increase of temperature in the elements will close the valve and a reduction in the temperature of the elements will 25 open said valve.

7 4. A thermostatic valve comprising a valve casing formed with a gas chamber, a plurality of independent ports leading from 30 said chamber, a gas supply leading to said chamber, a single valve to close communication between said chamber and all of the ports simultaneously and also at the same 35 time to close communication between the ports, pilot light ports leading from the gas chamber, said ports being uncontrolled by the said valve, thermostatic elements, and means connecting said elements to said 40 valve whereby an increase of temperature in the elements will close the valve and a reduction in the temperature of the elements will open said valve.

8 5. A thermostatic valve comprising a valve casing formed with a gas chamber, a plurality of concentric annular channels formed in the top of the gas chamber, the walls around said chambers forming valve seats at their lower edges, a single valve in 45 said chamber adapted to seat on said walls and close communication between said annular channels simultaneously, a supply port leading outwardly from each of said channels, thermostatic means for operating 50 the valve, whereby when the valve is seated the annular channels are at the same instant cut off from the gas chamber and from each other.

9 6. A thermostatic valve comprising a

10 valve casing formed with a supply chamber, 60 a plurality of independent ports leading from said chamber, a single valve to close communication between said chamber and the ports simultaneously and also at the same time to close communication between the ports, and thermostatic means for operating said valve.

15 7. A thermostatic valve comprising a valve casing formed with a gas chamber, a plurality of independent ports leading from 70 said chamber, a passage for each of said ports adapted to be connected to an independent burner, a valve to close communication between said chamber and the ports and also to close communication between 75 the ports, pilot light ports between the gas chamber and the outlet passages, said pilot light ports being uncontrolled by the said valve, and thermostatic means for operating 80 said valve.

20 8. A thermostatic valve comprising a valve casing formed with a gas chamber, a plurality of independent passages adapted to be connected to independent burners, a plurality of annular channels in the top of 85 the gas chamber, a supply port leading from each channel to each of said passages, a pilot light port leading from the chamber to each of said passages, a valve to close communication between the chamber and the channels and between the channels, the pilot light ports being uncontrolled by said 90 valve, thermostatic elements, and an operating lever operatively connecting said elements to the valve.

25 9. A thermostatic valve comprising a valve casing formed with a gas chamber, a plurality of independent passages adapted to be connected to independent burners, a plurality of annular channels in the top 100 of the gas chamber, a supply port leading from each channel to each of said passages, a pilot light port leading from the chamber to each of said passages, a valve to close communication between the chamber and 105 the channels and between the channels, the pilot light ports being uncontrolled by said valve, thermostatic elements, an operating lever operatively connecting said elements to the valve, and means for adjusting the 110 operative connection between the operating lever and the valve.

30 In testimony whereof I hereunto affix my signature in the presence of two witnesses.

ROBERT T. McCONLOGUE.
